CLAIM

We claim the ornamental design for a combined filters and panel for microwave, as shown and described.

DESCRIPTION

FIG. 1 is a perspective view of a combined filters and panel for microwave showing our new design;
FIG. 2 is a front elevation view thereof;
FIG. 3 is a rear elevation view thereof;
FIG. 4 is a left-side elevation view thereof;
FIG. 5 is a right-side elevation view thereof;
FIG. 6 is a top plan view thereof;
FIG. 7 is a bottom plan view thereof; and,
FIG. 8 is a partially enlarged view of portion “8” shown in FIG. 1.

The evenly-spaced broken lines depict portions of the combined filters and panel for microwave that form no part of the claimed design. The dot-dot-dash broken line shown in FIG. 1 is for the purpose of illustrating a partially enlarged view of FIG. 8 only and forms no part of the claimed design.
